UNITED STATES PATENT OFFICE.

ORAL J. LA COMBE, JR., OF NEGAUNEE, MICHIGAN.

KEY FOR STOP-BOXES.

1,135,297.

Specification of Letters Patent.

Patented Apr. 13, 1915.

Application filed May 8, 1914. Serial No. 837,275.

To all whom it may concern:

Be it known that I, ORAL J. LA COMBE, Jr., a citizen of the United States, residing at Negaunee, in the county of Marquette and State of Michigan, have invented certain new and useful Improvements in Keys for Stop-Boxes, of which the following is a specification, reference being had to the accompanying drawings.

10 This invention relates to certain improvements in keys for stop-boxes; and the object of the invention is to provide a device of this general character having novel and improved means whereby requisite illumination may be created in order to expedite the proper engagement of the crutch with the stop handle within the box.

15 The invention consists in the details of construction and in the combination and arrangement of the several parts whereby certain important advantages are attained and the device is rendered simpler, less expensive and otherwise more convenient and advantageous for use, all as will be hereinafter 20 more fully set forth.

The novel features of the invention will be carefully defined in the appended claims.

In order that my invention may be the better understood, I will now proceed to describe the same with reference to the accompanying drawings, wherein—

Figure 1 is an elevational view of a key constructed in accordance with an embodiment of my invention; and Fig. 2 is a fragmentary longitudinal sectional view taken through the device as disclosed in Fig. 1.

As disclosed in the accompanying drawings, 1 denotes an elongated tubular member of predetermined dimensions having one extremity formed into a crutch 2 adapted to engage with the stop handle in a well known manner, while adjacent the opposite extremity of the elongated member 1 is provided the cross bar 3 affording the requisite operating handles. The portion 4 of the member 1 forwardly of the cross bar 3 is enlarged and is adapted to receive a suitable battery 6, such battery being in electrical connection through the medium of the conductors 7 with the lamp 8 positioned within the tubular member adjacent its inner extremity or in close proximity to the crutch 2, and interposed in the conductors 7 is a suitable cir-

cuit closure 5 including a button projecting exteriorly of the portion 4 whereby the lamp 8 may be caused to flash when required.

In order that the lamp 8 may be normally protected, I mount in the inner portion of the crutch 2 the slide member 9 operating in and serving for a purpose which is believed to be clearly apparent. In order that the battery 6 may be maintained against displacement from within the enlarged portion 4, I provide the cap 10 adapted to detachably engage the outer end of such portion 4.

From the foregoing description, it is thought to be obvious that a key for a stop-box constructed in accordance with my invention is of an extremely simple and comparatively inexpensive nature and is particularly well adapted for use by reason of the convenience and facility with which it may be assembled and by reason of the effectiveness with which it performs its functions, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A key of the character described comprising a tubular member provided with an engaging extremity, an illuminating means positioned within such tubular member in close proximity to the engaging extremity of the member, and means for closing such engaging extremity of the member.

2. A key of the character described comprising a tubular member provided with a crutch, an illuminating means positioned within said tubular member in close proximity to the crutch, and a slide operatively engaged with the crutch and adapted to close the adjacent extremity of the tubular member.

In testimony whereof I hereunto affix my signature in the presence of two witnesses.

ORAL J. LA COMBE, JR.

Witnesses:

PETER F. BARASE,
JOHN T. BURNS.
